WILLIAM F. ZENTLER, OF CRESTWOOD, NEW YORK, ASSIGNOR TO SHELTON-JANCKE CORPORATION, OF NEW YORK, N. Y., A CORPORATION OF NEW JERSEY.

HAIR WAVER.

Application filed July 20, 1923. Serial No. 652,738.

To all whom it may concern:

Be it known that I, WILLIAM F. ZENTLER, a citizen of the United States, and resident of Crestwood, in the county of Westchester and State of New York, have invented certain new and useful Improvements in Hair Wavers, of which the following is a specification.

The invention relates to a hair waver or curling rod for use in the art of permanent hair waving and designed for receiving a strand of hair which is coiled spirally on such wavers prior to encasing the hair in a heating device.

In the art of permanent hair waving, as at present practiced, it is usual to provide a thin rod, circular in cross-section, and preferably tapered towards the end adapted to be disposed adjacent the person's head so as to accommodate the thicker portions of the strand of hair adjacent the head and in this way provide for uniformity or at least substantial uniformity in the length of the formed wave in the finished hair. One difficulty in the practical operation of hair waving has been the necessity of tying the ends of the strand of hair to the waver and several attempts have been made to eliminate the necessity of such tying operations. The suggested substitutes for the usual tying operation usually provides for some form of clamp, but these clamps are expensive; are difficult to operate in the presence of a large mass of loose hair; are cumbersome; take up room adjacent the head and thus act to reduce the number of curlers or wavers which can be positioned at one time on the person's head.

Accordingly, the primary object of the invention is to provide a hair waver of the type outlined, which will retain the advantages inherent in the approved tapered form of waver with its necessary circular cross-section, and which, at the same time, can be quickly secured to the hair strand with the hair strand curled thereon and without necessity of using either separate tying means nor the bulky clamps now known in the art.

In general the invention features simplicity in construction in the elimination of projecting parts which may become entangled in the adjacent hair and the providing of a form of waver which can be

cheaply constructed and supplied to the market in competition with present forms of similar articles.

Another object of the invention is to provide a form of hair waver which will not only facilitate a positive securing of the hair strand thereto, but which will also facilitate the ready removal of the strand from the waver, following the waving operation.

In the practicing of permanent hair waving it has always been difficult to wave the hair up close to the person's scalp due to the necessity of providing a sufficient length of hair to tie the same to the waver before the strand is wrapped about the same. Accordingly, the present disclosure features a construction at one end of the waver which will permit the end to be brought close to the scalp, and in this way it is possible to start the wave in the hair closer to the head than has been heretofore possible.

Still another object of the invention is to provide a hair waver all parts of which are readily accessible for cleaning and incidental to the desideratum to provide for a sanitary article the disclosure features a construction which is free of pockets or close angles which might collect dirt and is free of sharp edges which might injure the operator in manipulating the waver.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:—
Figure 1 is a view in side elevation of a waver constituting a preferred embodiment of the invention and shown in operative position with a strand of hair wrapped on and secured to the same;

Figure 2 is a transverse sectional view through the waver shown in Figure 1 and taken on the line 2—2 of Fig. 1 looking in the direction indicated by the arrows; and

Figure 3 is an enlarged view of the waver shown in opened position.

In the following description and in the claims, parts will be identified by specific

names for convenience of expression but they are intended to be as generic in their application to similar parts as the art will permit.

In the drawings there is shown a waver 5 10 which, when the parts thereof are assembled in operative position, resembles conventional forms of such wavers in that it is a long rod circular in cross-section, as shown in Figure 2, and gradually tapers from an 10 outer end 11 towards its inner end 12. It is understood that the reduced end 12 is designed to be positioned adjacent the head of the person, whose hair is to be waved and a strand of hair A is wrapped spirally on 15 the waver and otherwise treated following conventional practices.

The distinctive feature of the present disclosure is that the waver is split along its axis to form two similar sections 13 and 20 14 with inner oppositely disposed faces 15 and 16 substantially in contact when in operative position. The face 16 is provided adjacent the outer end 11 of the waver with a roughened surface 17, herein shown to be 25 formed of transversely disposed corrugations formed of spaced apart depressions or grooves 18.

The two sections 13 and 14 are pivotally connected at the small end 12 by means of a pivot pin 19. It is a feature of this disclosure that the pivot pin is positioned as close to the end as is physically possible to position this pin and still maintain the ends connected. It is also suggested that the 35 pin be slightly longer than the aperture in which it is positioned, so that the pin will provide a loose pivotal connection thus permitting a slight separation of the faces 15 and 16 at the pivoted end of the waver. This 40 construction permits the ready insertion of the flat portion B of the strand of hair between the two sections of the waver and close to the end of the same and to the person's head as shown in Figure 1.

45 At the outer end 11 of the waver the faces 15 and 16 are bevelled outwardly to provide a V-shaped forked opening 20 constituting a guide for facilitating the insertion of the free end C of the strand into position between the surfaces 15 and 16 and where it is held frictionally by the roughened portion of the latter.

In operation it will be understood that a portion of the hair to be waved is gathered 55 into a strand and with the waver in the opened position shown in Figure 3 the portion B of the strand adjacent the head is passed between the sections of the waver and the end of the waver is positioned as 60 close as is possible to the head of the person. The sections of legs of the waver are then closed into parallel relation and the strand coiled spirally on the assembled waver, as is usual in practicing the art of waving hair.

65 The free end C of the strand is then drawn

through the guiding slot at the outer end of the waver and is pulled into position to be clamped between the two parts of the waver. It is understood that the turns of the strand engaging the outer surface of the 70 waver acts to hold the sections in position and acts therethrough to hold the free end C of the strand clamped between the jaws formed by the sections. The hair waving operation is completed following conventional practice after which the curled strand is removed from the waver. This is quickly effected simply by withdrawing the end C from its clamped position thus loosening the hair curl. The waver may then be 80 grasped at its pivoted end and withdrawn axially from the formed and loosened curl. As there are no projecting parts from the waver this removal can be effected without causing the same to become entangled with 85 other wavers or with any loose hair present.

By means of a device of the type disclosed it is possible to form perfect marcel waves which will be free from kinks and which will extend in a natural undulation practically up to the scalp. As tying operations have been eliminated the process can be practiced quickly and any danger of cutting the operator's fingers has been 90 eliminated. In one practical form of the 95 invention the rod is made of aluminum which has the advantage of lightness in weight and its non-resiliency tends to prevent deformation of the formed wave.

While I have shown and described, and 100 have pointed out in the annexed claims, certain novel features of my invention, it will be understood that various omissions, substitutions and changes in the form and details of the device illustrated and in its 105 operation may be made by those skilled in the art without departing from the spirit of the invention.

Having thus described my invention, I 110 claim:

1. A hair waver for use in the art of permanent hair waving, said waver being relatively long, tapering towards one end and circular in cross-section, said waver being divided on a plane containing the longitudinal axis of the waver to form the waver of two similar sections with flat contacting sides and rounded outer sides, and means pivotally connecting the sections adjacent the smaller end of the waver.

2. A hair waver for use in the art of permanent hair waving, said waver being relatively long, tapering towards one end and circular in cross-section, said waver being divided on a plane containing the longitudinal axis of the waver to form the waver of two similar sections with flat contacting sides and rounded outer sides, means pivotally connecting the sections adjacent the smaller end of the waver, the opposite end 120

of each section being bevelled on its inner side and said bevelled sides coacting to form a V-shaped notch for receiving an end of the coil of hair wrapped about the waver 5 and for guiding the same into a clamped position between the flat sides.

3. A hair waver comprising a pair of legs pivotally connected at one end, said legs being loosely pivoted so as to be separated 10 slightly to receive a strand of hair between the same at one end and coacting when in parallelism to form a long tapered rod substantially circular in cross-section and reducing in cross-section towards the pivoted 15 end for coiling the strand of hair about the same.

4. A hair waver comprising a pair of legs disposed in parallelism having flat contacting inner surfaces and rounded outer surfaces, said inner surfaces at one end being bevelled outwardly and coacting to provide a 20 V-shaped forked opening, said legs adapted to have a strand of hair coiled about the same with the ends of the strand disposed 25 between the flat surfaces and held in place between the legs by the turns of the coil of hair wrapped about the waver and one end guided into said position through said forked opening.

30 5. A hair waver comprising a pair of legs disposed in parallelism having flat contacting inner surfaces and rounded outer surfaces, said legs adapted to have a strand of hair coiled about the same with the ends of

the strand disposed between the flat surfaces and held in place between the legs by the turns of the coil of hair wrapped about the waver, one of said flat surfaces being roughened to assist in holding the hair strand in place. 35

6. A rod for use in permanent hair waving being substantially circular in cross-section and divided along its axis to form two similar sections, and a pivot pin loosely connecting the sections adjacent one end to 40 permit the separation of the sections at the pivoted end and thus permit the insertion between the sections and adjacent the pin of a flat portion of the strand of hair wrapped about the rod. 45

7. A hair waver comprising two separate sections coacting to form a long tapered rod substantially circular in cross-section, the outer curved surface of said waver being continuous and adapted to have a strand of 50 hair coiled about the same with turns of progressively reduced diameters, means for securing the sections to each other and said sections coacting to constitute a clamp for securing the waver to a flat end portion of 55 the hair strand to be waved. 60

Signed at New York city, in the county of New York and State of New York, this 5th day of July, A. D. 1923.

WILLIAM F. ZENTLER.
